CIGARETTE CONTAINER CONSTRUCTION

Carl Julius Lagerholm, Attleboro, Mass., assignor
to Evans Case Company, North Attleboro,
Mass., a corporation of Massachusetts

Application March 24, 1930. Serial No. 438,302

9 Claims. (Cl. 206—41)

This invention relates to containers for cigarettes and the like, and, with regard to the more specific features, to devices for use with the original package in which the cigarettes are contained.

One of the objects thereof is to provide a simple and inexpensive device of this character which is of a distinctly practical nature. Another object is to provide a device of this type which will serve to protect the cigarettes and make them readily accessible. Other objects will be in part obvious and in part pointed out hereinafter.

The invention accordingly consists in the features of construction, combination of elements and arrangements of parts all as will be herein illustratively described, and the scope of the application of which will be indicated in the following claims.

20 In the accompanying drawing in which are shown the features of a selected embodiment of this invention:

Fig. 1 is a sectional view substantially on the line 1—1 of Fig. 2;

25 Fig. 2 is a sectional view substantially on the line 2—2 of Fig. 1;

Fig. 3 is a sectional view on the line 3—3 of Fig. 1, and

Fig. 4 is a partial front elevation.

30 Referring to the drawing, an open top receptacle 10 is adapted to fit about a package of cigarettes or to contain the contents thereof. This receptacle is preferably made of any suitable flexible material such as leather or fabric, and a narrow band 11 of metal or other substantially rigid material extends partially about the rim thereof.

Within this receptacle 10 is a resilient wire member having parallel arms 12 connected one with another by the transverse portion 13 at the rear of the device. The forward ends of the arms 12 lead respectively to a pair of downwardly extending loops 14 flattened as indicated at 15 and terminating at their upper rear ends in a transverse portion 16 adjacent the portion 13. These loops, being of spring metal, tend to hold the position shown in full lines in Fig. 1 of the drawing, but their rearward portion 17 may be pressed forwardly into substantially the position indicated in broken lines in that figure.

40 The arms 12 may be secured to the under face of the corresponding portions of inwardly projecting flanges 18 on the band 11 by solder or any other convenient manner. The loops 14, including the arms 12, constitute open loops in the sense that the

adjacent ends are not connected, and the loops are preferably located in parallel planes. While actually the two loops are shown as made from a single piece of wire, so far as certain features of the invention are concerned they might be separate, although certain advantages are secured by the construction shown.

45 A substantially dome shaped cover 20 for the receptacle is pivotally mounted on the transverse portion or bar 13 of this wire member, and on the front wall (Fig. 4) of this cover is formed a depending flange 21 which, in the closed position of the cover, is adapted to lie between the ends 22 of the rim and substantially fill the gap therebetween at the front of the receptacle. Thus the band 11 with the flange 21 substantially completely encircles the rim of the receptacle. A plate 30 is secured to the rear portion of the cover 20 and on this plate are provided a pair of loops 31 and an offset portion 32 having its lower extremity bent to form another loop as 33. The loops 31 loosely encircle the portion or bar 13 to form the hinge connection for the cover, and the loop 33 encircles in the same manner the portion or bar 16 on the wire member.

50 In this construction it will be seen that the cover 20 and the loops 31 are joined together, the angular relationship of these parts being dependent upon the relative disposition of the free ends of the loops, and under the urge in a rearward direction of the bar 16, the cover 20 is normally held tightly in closed position upon the frame or band 11, as shown in full lines in the drawing. When, however, the rear upright portions 17 of the spring loops are pressed in a forward direction into substantially the position indicated in broken lines in Fig. 1, the cover is quickly swung about the bar 13 into the open or substantially upright position as indicated in dotted lines. Upon the release of this pressure, the cover is instantly closed as the members 17 return to their normal position.

55 The arms 12 and the other portions of the spring member except the bar 13 and the portions of the arms 12 immediately adjoining, are preferably spaced sufficiently from the band 11 to permit the upper margin 35 of the receptacle to lie therebetween as shown. This margin may be attached to the band in any suitable manner. The cigarettes are placed in the receptacle 10 in an upright position substantially as indicated at 36, and their upper portions 37 project above the band 11. These projecting ends of the cigarettes lie within the dome shaped cap 20 when such cap is in closed position and are fully pro-

60

105

110

tected thereby. When the cap is raised in the manner described, these projecting ends may be readily grasped and the cigarettes withdrawn.

When the device is intended to be used with the original package in which the cigarettes are packed, the receptacle 10 may be omitted. The top wall and the upper portion of the side walls of the package are torn off and the spring loops 14 are then slid between the corresponding side walls of the package and the cigarettes until the upper edge of the package lies within the band 11 in the same manner as is shown for the rim of the receptacle. Sufficient of the side walls of the package should be removed so that the cigarettes will project within the dome shaped cap approximately the amount indicated in the drawing. The spring loops not only act to hold the package in shape, but also serve to hold the package in its proper position relative to the device.

20 When the portions 17 of the wire member are pressed inwardly to raise the cover 20, the bar 16 might be expected to slightly jam or compress the portions of the cigarettes opposite thereto, but this does not occur to any material extent as the cut away portion of the band 11 between the ends 22 permits a limited yielding or bulging of the portion of the rim of the package or receptacle therebetween. The cover 20 has risen sufficiently before this jamming action would become material to withdraw the flange 21 from its position between these ends, and therefore it does not appreciably interfere with the yielding action of the rim.

The term "dome" is herein used in connection with the cover in its broad sense to include any chambered or elevated top cover or a cover shaped to provide therein a space into which the contents of the receptacle may project.

It will be evident from the foregoing description that the device forming the subject matter of the invention is simple and compact in construction, may be economically produced, and is of an essentially practical nature. The cigarettes are adequately protected and are readily accessible. The device is easily operated and may be conveniently carried in the pocket.

As many other embodiments may be made of the features of the above construction without departing from the scope of the invention, it is 50 to be understood that all matter herein set forth or shown in the accompanying drawing is to be interpreted as illustrated and not in a limiting sense.

I claim:

55. 1. In a device of the character described, in combination, a flexible receptacle shaped to contain a plurality of cigarettes, a dome shaped cover to said receptacle, a pair of hinge elements attached to said cover, a pair of open loops the 60 ends of which are connected to said hinge elements in the inside of said receptacle and disposed adjacent its side walls, the loops being flat and so shaped as upon compression to raise the cover.
65. 2. In a device of the character described, in combination, a narrow body portion adapted to partially encircle the top of a cigarette package, a substantially dome shaped cover member mounted on said body portion and movable relative thereto, a pair of fulcrum members whose axes are parallel and close together and parallel to the plane of said cover said fulcrum members being connected to said cover, and spring means located substantially in a plane normal to the 70 axes of the fulcrum members and connected to

both of said fulcrum members and imparting to said fulcrum members a couple and adapted for insertion within the outer wrapper of a cigarette package and acting to raise said cover member when said package is compressed.

3. In a device of the character described, in combination, a narrow body portion adapted to partially encircle the top of a cigarette package, a substantially dome shaped cover member mounted on said body portion and movable relative thereto, a pair of fulcrum members whose axes are parallel and close together and parallel to the plane of said cover said fulcrum members being connected to said cover, and a pair of open loops whose respective ends are connected to said fulcrum members, one end of each loop being connected to one fulcrum member and the other end of each loop being connected to the other fulcrum member and said loops being adapted respectively for insertion between the side walls of a package of cigarettes and the cigarettes, and adapted on movement to open said cover member and upon release to close the same.

4. In a device of the character described, in combination, supporting means adapted to coact with the top end of a package of cigarettes, a dome shaped cover member movable on said supporting means, a pair of fulcrum members whose axes are parallel and close together and parallel to the plane of said cover said fulcrum members being connected to said cover, and a pair of open loops the open ends connected to said fulcrum members said loops being also connected to said supporting means and said loops being shaped to fit inside the side walls of said package and outside of the cigarettes therein, movement of said loops acting to raise said cover member.

5. In a device of the character described, in combination, supporting means adapted to coact with the top end of a package of cigarettes, a dome shaped cover member movable on said supporting means, a frame connected to said supporting means and shaped to fit the inside of the side walls of said package and the outside of the cigarettes therein, and a pair of fulcrum members whose axes are parallel and parallel to the plane of said cover said fulcrum members being connected to said cover and also to said frame, said frame acting upon compression of the package to raise said cover member, and upon release to close the same.

6. In a device of the character described, in combination, supporting means adapted to coact with the top end of a package of cigarettes, a dome shaped cover member, a hinge mounted on said supporting means, another hinge connected to said first hinge, and wires connected to said hinges and depending therefrom for insertion within the outer wrapper of the cigarette package, whereby the cover is raised when pressure is exerted on said package.

7. In a device of the character described, in combination, a cigarette case the side and end walls of which are continuous and entirely made of flexible material, a dome-shaped cover for said cigarette case, and means operable by compression of the end walls of the cigarette case for opening the cover.

8. In a device of the character described, in combination, a cigarette case the side and end walls of which are continuous and entirely made of flexible material, a dome-shaped cover for said cigarette case hinged at one end of said cigarette case and having a downwardly extending flange at the other end, a broken rim on said

cigarette case at the top thereof, the said flange being adapted to fit between the ends of said rim, and means upon compression of the end walls of said cigarette case to raise the cover, 5 cigarettes that are pressed inwardly at one end being free to press the flexible material outwardly at the other end between the broken ends of the rim.

9. In a device of the character described, in 10 combination, a flexible cigarette case the walls

of which are continuous, a band encircling the top of said cigarette case except for a portion of one end wall thereof, a cover hingedly connected to said band, and means in said cigarette case connected to said cover and to said band for 80 opening said cover upon pressing inwardly one end wall of said cigarette case, the gap between the ends of the band permitting said pressure without crushing the cigarettes.
